FIG 3

UNITED STATES PATENT OFFICE

2,644,911

SAFETY SYSTEM FOR LUMINESCENT TUBES

Rudolph C. Hultgren, Chicago, Ill., assignor, by
mesne assignments, to Bert C. Pretzer, Detroit,
Mich., and Rudolph C. Hultgren, Chicago, Ill.,
jointly

Application June 7, 1947, Serial No. 753,246

3 Claims. (Cl. 315—187)

1

The present invention relates to systems and circuits for the operation of luminescent electric tubes, and constitutes an improvement upon the construction described and claimed in my copending application, Serial No. 587,945, filed April 12, 1945, now abandoned.

Operating potentials, in the neighborhood of 600 volts, required for certain cold-cathode lighting tubes are regarded as unsafe and my prior application discloses a safety fixture and system for protecting persons from the high voltage conductors. It is desirable for improved economy of installation and operation to employ two tubes in series, but the higher circuit voltage required for such series operation has, understandably, been regarded as even more dangerous.

One object of the present invention is the provision of an improved system in which the hazards of such a series system are no greater than those of the shunt system.

Another object is the provision of a safety control for such a series system so that persons will be effectively protected from contact with energized high voltage conductors.

A further object is the provision of an improved cold-cathode, luminescent-tube system, and the provision of an improved safety control for such systems.

In the preferred embodiment of my invention, the ballast transformer has a separate, insulated secondary winding for each series pair of luminescent tubes, and the connection between the two tubes, that is the mid-point of the load, is connected to the primary circuit. Furthermore, this connection to the primary is accomplished by a circuit controlling socket that interrupts the primary to deenergize the transformer whenever a tube is removed.

These and other objects and advantages will appear from the following description of a specific construction which illustrates the manner in which the invention may be carried out.

In the drawings:

Fig. 1 is a view, partly in section of a lighting fixture and luminescent tubes therein;

Fig. 2 is a schematic diagram showing the luminescent-tube circuit of my present invention; and

Fig. 3 shows a modification of the circuit of Fig. 2.

In Fig. 1 a housing 10 contains an insulating plate 12 which supports four helical spring sockets 14. A second housing 16 contains an insulator 18 which supports four split-cone

2

sockets 20 of the type shown in my application, Serial No. 743,248, filed April 23, 1947, now abandoned. The sockets 14 and 20 are adapted to receive and hold luminescent tubes 22. A tube is first inserted through an opening 24 in housing 10 into a socket 14, and forced into the socket to distend it enough that the other end of the tube 22 may be inserted through a similar opening 26 in housing 16 into a socket 20, where it is firmly seated by the force of the spring of socket 14. Metal terminal caps 28 on the tubes 22 provide the electrical connections of the tubes to the sockets 14. A similar cap 30 on the other end of each tube bridges the two halves of its socket 20. These split-cone sockets constitute switches and are connected in series by straps 32 so that the circuit is complete only when the tube-caps 30 are seated in all four of the sockets, as is described in said application, Serial No. 743,248.

The tubes 22 are of the cold-cathode, instantaneously-starting type, operating with about 450 volts R. M. S. drop across the tube but requiring a somewhat higher total circuit voltage, the difference being absorbed in a reactance.

In Fig. 2, the four tubes 22 are shown schematically in my improved circuit. A transformer 40 includes a primary winding 42 and two similar secondary windings 44 and 46 insulated from the primary winding and each of which has considerable self inductance to provide the ballast needed for limiting the current to the tubes 22. Any number of such secondary windings may be used. The secondary windings may have additional inductive or capacitive ballast devices connected in series with them as is well known in the art. Thus, a condenser 48 in series with winding 44 provides ballast and improves the power factor of the current drawn by the primary winding. This winding 44 supplies a load consisting of two tubes 22 which at their ends remote from winding 44 (their right ends as viewed in Fig. 2) are connected to the primary circuit. Thus, although winding 44 may deliver a total of about 900 volts under load, only about half of that can appear between either left-hand tube terminal 28 and ground because one conductor of the 110 volt input will be at or near ground potential. Furthermore, should one tube fail to operate the other one will be thereby prevented from operating, and under such condition, winding 44 will be effectively isolated by the extremely high resistances of the unlit tube. Not only does the socket construction of Fig. 1 prevent contact with the con-

ductors when tubes 22 are in place, but the fact that winding 44 is insulated so that it has its only connection to other parts of the circuit through tubes 22, insures that at least one tube 22 will be in the circuit that feeds a ground fault at a 5 socket 14 or a terminal of winding 44.

The primary circuit for energizing transformer 40 includes all four sockets 20 connected in series with winding 42. Therefore, whenever any one of tubes 22 is removed the primary circuit is opened and the secondary windings de-energized. Consequently it is impossible for a 10 person to come into contact with high voltage when a tube is removed unless socket 20 is tampered with, as by the insertion of a conductor 15 therein. But even in that case that person can receive the high voltage only through a circuit that includes the other tube. In this respect, the present series system is even more safe than the shunt system of my prior application, Serial 20 No. 587,945, previously referred to, which employs a lower secondary voltage at the transformer.

In the circuit modification of Fig. 3, an impedance element or condenser 50 is connected 25 from ground 52 to a part of winding 44 intermediate the terminals thereof, such as the mid-voltage point, the core 43 of the transformer being also grounded as indicated at 54. Alternatively, condenser 50 may be connected between 30 said winding 44 and one of the terminals of primary winding 42. Condenser 50 has an impedance, at the frequency of the supply voltage, which is high compared to that of the tubes 22 when they are operating, but low compared to 35 that of those same tubes when unlit. Accordingly, when the tubes are unlit, the path through condenser 50 will effectively tie the mid-voltage point of the winding to ground and so prevent the full voltage of the winding from appearing 40 between either socket 14 and ground when one tube is defective or when a tube is removed and its socket 20 is tampered with for closing the primary circuit. When the tubes are lit, condenser 50 will be a high impedance shunt to a 45 part of the circuit and so have little effect.

The circuit of Fig. 2 has the advantage that the winding 44 is better isolated from the other windings.

Thus the present invention provides the safety of the shunt system but an economy of the series system. Two tubes in series will strike at less than twice the voltage required for two tubes, because the voltage will not initially divide equally between the two tubes so that they light in turn. Thus two tubes requiring 750 volts for shunt operation may be operated in series on 1300 volts. In addition, with the circuit of Fig. 3, the primary voltage is added to that of one of the two tubes for aiding its starting. After that one tube starts, its impedance drops to increase the voltage applied to the other so that it starts too.

While I have shown and particularly described a preferred embodiment of my invention, the specific features thereof, and the detailed explanation should not be construed as limiting except as required by the claims.

What I claim as new and desire to protect by Letters Patent of the United States is:

1. A system for energizing a pair of luminescent electric tubes from an alternating current power supply comprising, a transformer including a primary winding and a secondary winding separate and conductively isolated there-

from, means for connecting the primary winding to the alternating current power supply, means for connecting the pair of luminescent electric tubes in series with each other and in series with the secondary winding only of said transformer including means for connecting one end of one tube to one end of the secondary winding and including a condenser in series, means for connecting one end of the other tube to the other end of the secondary winding and means for connecting the other ends of the tubes together, said means for connecting the primary winding to the alternating current supply including said means for connecting the other ends of the tubes together so that the connection between said other ends of the tubes is at no time higher than the potential of the alternating current power supply to the primary winding and so that when the connection between said other ends of the tubes is broken, the connection between the primary winding and the alternating current power supply is also broken.

2. A system for energizing a pair of luminescent electric tubes from an alternating current power supply comprising, a transformer including a primary winding and a secondary winding separate and conductively isolated therefrom, means for connecting the primary winding to the alternating current power supply, means including a condenser for connecting the center of the secondary winding to ground, means for connecting the pair of luminescent electric tubes in series with each other and in series with the secondary winding only of said transformer including means for connecting one end of one tube to one end of the secondary winding and including a condenser in series, means for connecting one end of the other tube to the other end of the secondary winding and means for connecting the other ends of the tubes together, said means for connecting the primary winding to the alternating current supply including said means for connecting the other ends of the tubes together so that the connection between said other ends of the tubes is at no time higher than the potential of the alternating current power supply to the primary winding and so that when the connection between said other ends of the tubes is broken, the connection between the primary winding and the alternating current power supply is also broken.

3. A system for energizing a plurality of pairs of luminescent electric tubes from an alternating current power supply comprising, a transformer including a primary winding and a plurality of secondary windings separate and conductively isolated therefrom, one secondary winding being provided for each pair of luminescent electric tubes, means for connecting the primary winding to the alternating current power supply, a plurality of connecting means each comprising means for connecting the luminescent electric tubes of each pair in series with each other and in series with its associated secondary winding only of said transformer including means for connecting one end of one tube to one end of the secondary winding, means for connecting one end of the other tube to the other end of the secondary winding and means for connecting the other ends of the tubes together, said means for connecting the primary winding to the alternating current supply including all of said means for connecting the other ends of the tubes together so that all of

said connections between said other ends of the tubes are at no time higher than the potential of the alternating current power supply to the primary winding and so that when any of said connections between said other ends of the tubes are broken, the connection between the primary winding and the alternating current power supply is also broken.

RUDOLPH C. HULTGREN.
